UNITED STATES PATENT OFFICE

CLEN S. HUMPHREY, OF BROOKLYN, NEW YORK, ASSIGNOR TO CONTINENTAL CAN COMPANY, INC., OF NEW YORK, N. Y., A CORPORATION OF NEW YORK

CONTAINER COVER

Application filed November 1, 1927. Serial No. 230,288.

This invention relates to receptacles or containers for packaging merchandise and has particular reference to the cover construction of a container of this character.

5 The invention primarily comprehends a cover for containers which includes means defining a compartment for holding a pamphlet, folder, or other advertisement or direction-bearing elements of this nature in such a manner that the same are displayed when the cover is removed from the container.

10 The invention furthermore comprehends a container cover in which the means coacting therewith to define the receiving compartment for a pamphlet or the like, serves in the capacity of a sealing gasket for preventing leakage of the contents or for excluding air therefrom.

15 Other objects reside in the simplicity of construction of the cover, the economy with which the same may be produced, and the general efficiency derived therefrom.

20 With the above recited and other objects in view, reference is had to the following description and accompanying drawings in which there is exhibited one example or embodiment of the invention, while the appended claims define the actual scope of the invention.

25 In the drawings—

Figure 1 is a side view of a container having a cover constructed in accordance with the invention and illustrating the cover removed from the container;

30 Fig. 2 is a vertical sectional view through the container with the cover applied thereto;

Fig. 3 is an inner face view of the container cover.

35 Referring to the drawings by characters of reference, 10 designates a container body of the usual open ended type, the said body being preferably of circular configuration and having one or more threads or thread sections 11 on the outer periphery adjacent its upper open end. The cover 12, which constitutes the present invention, includes a top wall 13 having an upwardly offset medial portion 14 and a depending marginal flange 15. The flange 15 is provided with internal

threads or thread sections 16 which are designed upon turning movement in one direction of the cover relative to the body, to establish a locking connection between the cover and container body. The cover flange 15 is further provided with a plurality of circumferentially spaced inwardly projecting bead sections 17 which are slightly spaced from the top wall 13. A disk 18 of yieldable resilient material is snugly fitted within the cover with the peripheral or marginal edge positioned between the bead section 17 and the top wall so that the disk together with the offset portion 14 of the top wall 13, defines a compartment 19 within which a pamphlet, folder, or the like, 20 is adapted to be placed, said pamphlet, folder or the like being adapted to contain advertising matter or instructions as to the use of the contents of the container body. In order to display the pamphlet, folder or the like when the cover is removed from the receptacle body, the disk 18 is formed with an opening 21 preferably at the center thereof, which opening also affords means for inserting the finger therethrough to effect the displacement and withdrawal of the disk from the cover to remove the pamphlet or folder 20. If desired, the outer periphery of the cover flange 15 between the bead sections 17, may be knurled 80 as illustrated at 22, to afford a means for gripping and rotating the cover in either a direction to lockingly engage the flange sections 11 and 16 or to disengage the same. It should also be noted that the disk 18 serves 85 in the capacity of a gasket for sealing the cover and container body against spilling of the contents or the ingress of air thereto.

While the invention primarily comprehends a container or receptacle for cold cream, cosmetics, salves or like, and the container body, is shown as of circular formation, it is nevertheless to be understood that the invention is not restricted to such a use or shape, as the same is merely illustrative of 90 the general use to which the invention has been designed.

What is claimed is:

1. A container including a body having an open exteriorly threaded upper end, and a

100 flange 15 provided with internal threads or thread sections 16.

cover therefor including a top wall having an upwardly offset medial portion conforming substantially to the size of the opening of the container body and a marginal flange having mating internal threads for connecting the cover and body, and a disk frictionally fitted within the cover flange against the top wall and defining together with the upwardly offset medial portion, a compartment approximately the size of the opening of the container body for holding a pamphlet, folder or the like.

2. A container including a body having an open exteriorly threaded upper end, a cover therefor including a top wall having an upwardly offset medial portion and a marginal flange having mating internal threads for connecting the cover and body, and a disk frictionally fitted within the cover flange against the top wall and defining together with the upwardly offset medial portion, a compartment approximately the size of the opening of the container body for holding a pamphlet, folder or the like, the said disk having a central aperture constituting respectively means for displaying the pamphlet or folder, and means for the insertion of a finger to displace the disk for effecting the removal of the pamphlet or folder.

3. A container including a body having an open exteriorly threaded upper end, a cover therefor including a top wall having an upwardly offset medial portion and a marginal flange having mating internal threads for connecting the cover and body, and a disk frictionally fitted within the cover flange against the top wall and defining together with the upwardly offset medial portion, a compartment which approximately covers the opening of the container body for holding a pamphlet, folder or the like, the said disk having a central aperture constituting respectively means for displaying the pamphlet or folder and means for the insertion of a finger to displace the disk for effecting the removal of the pamphlet or folder, the said disk also serving as a gasket disposed between the top wall of the cover and the open end of the container body for sealing the container.

4. A container including a body having an open exteriorly threaded upper end, and a cover therefor including a top wall having an upwardly offset medial portion and a marginal flange, and mating internal threads for connecting the cover and body, and a disk fitted within the cover flange against the top wall and defining together with the upwardly offset medial portion, a compartment which covers substantially the opening of the container body for containing a pamphlet or folder, the said flange having circumferentially spaced inwardly projecting beads between which and the top wall of the cover, the disk is frictionally held.

5. A container having an open upper end

and a cover therefor including a top wall having an upwardly offset medial portion and a marginal depending flange, said flange having circumferentially spaced inwardly projecting bead sections spaced from the top wall, and a disk within the cover, frictionally retained between the top wall and the bead sections and defining together with the upwardly offset medial portion of said top wall, a compartment which covers substantially the opening of the container body for containing a pamphlet or the like, said disk having a central opening for displaying the pamphlet therethrough and affording means for the insertion of the finger therethrough to displace the disk for effecting the removal of the pamphlet.
